B. Boardman,
Wiring Blinds.

No 18,080.

Patented Sep. 1, 1857.

UNITED STATES PATENT OFFICE.

BYRON BOARDMAN, OF NORWICH, CONNECTICUT.

MACHINE FOR WIRING BLIND-RODS.

Specification of Letters Patent No. 18,080, dated September 1, 1857.

To all whom it may concern:

Be it known that I, BYRON BOARDMAN, of 5
Norwich, in the county of New London and
State of Connecticut, have invented a new
and Improved Machine for Wiring Blind-
Rods; and I do hereby declare that the fol-
lowing is a full, clear, and exact description
of the same, reference being had to the an-
nexed drawings, making a part of this speci-
fication, in which—

Figure 1, is a side view of my improve-
ment. Fig. 2, is a front view of ditto, the
staple feeding device being bisected as indi-
cated by the line (y) (y) Fig. 1. Fig. 3, is
15 a vertical section of ditto, taken in the line
(x) (x) Fig. 2. Fig. 4, is a detached front
view of the guides between which the
staples are driven into the rods. Fig. 5, is a
20 detached view of one of the rods by which
the guides are adjusted.

Similar letters of reference indicate cor-
responding parts in the several figures.

My invention consists in the employment
or use of two feeding devices, one of which
25 feeds the staples between the guides which
conducts the staples to the rod, and the other
feeds the rod along underneath the guides
to receive the staples, so that they may be
driven into the rod at equal distances
30 apart—the above parts being used in con-
nection with a driving device for forcing
the staples into the rod, and the whole so
arranged as to operate automatically and in
a perfect and expeditious manner.

35 To enable those skilled in the art to fully
understand and construct my invention, I
will proceed to describe it.

A represents a cast metal frame, the form
of which is plainly shown in the drawings,
40 and B represents a bent or V-shaped lever
which is pivoted in the frame A as shown
at (a). A foot strap C is attached to the
end of the lower bar (b) of the lever B
against which bar a spring (c) bears, said
45 spring having a tendency to keep the outer
ends of the lever thrown upward as far as
they are allowed to be elevated. This cul-
minating point is determined by the lower
bar (b), the outer end of which is fitted and
50 works in a slot (d) in the front upright (e)
of the frame A as shown plainly in Figs. 2
and 3.

The outer end of the upper bar (f) of the
lever B works in a slot made in an inclined
55 bar (g) which is at the end of an inclined
bar (h), the bar (h) being connected with

the back upright (i) of the frame A. The
lower end of bar (g) is connected to the
upper end of upright (e) as plainly shown
in Fig. 3. From the inclined bar (g) a lat-
eral or horizontal bar (j) projects. This
60 bar is grooved and a slide D is fitted therein,
said slide being secured at any desired point
in the bar (j) by means of a screw (k)
which passes into the end of the bar (j) 65
and a screw (l) which is attached to the
slide and passes through the slot in the bar
and has a thumb nut (m) on its end. To
the outer side of the slide D a spring (n)
70 is attached. This spring bears against a
lever E which is attached to the slide by a
fulcrum pin (o). The spring (n) has a
tendency to keep the lower end of the lever
E against the lower part of the face of the
75 horizontal bar (j) as shown at (a*) in Fig. 1.

To the upper end of the front upright
(e) a horizontal bar (p) is attached, and a
bed F is placed on this bar (p). The bed
F is parallel with the bar (j) and is made
80 adjustable by means of set screws (q) which
pass through slots in the bed and into the
bar (p). The bar (p) is also made adjust-
able on the upper end of the upright (e)
by means of set screws (r). See Fig. 1. A
85 longitudinal groove (s) is made in the bed
F to receive the rod G to be wired, and the
rod is retained, or kept in the groove by a
spring H which bears upon the upper sur-
face of the rod, said spring being attached
90 to a projection (t) on the bed. See Fig. 2.

From the inclined bar (g) near its upper
end a horizontal bar (u) projects. This
bar (u) has a bent lever I attached to it,
95 said lever working on a fulcrum pin (v)
attached to the bar. To the lower end of
the vertical arm (w) of the lever a bar J
is pivoted, at one end, the other end of the
bar working on a bar (b') attached to the
100 slide D. The end of the bar J that works
on the bar (b') projects inward and passes
a short distance underneath the bar (j) as
shown in Fig. 1. The horizontal arm (e')
of the lever I passes over the slot in the
105 inclined bar (g) as shown in Fig. 2.

The inclined bar (g) has a die or rod K
fitted within it, and the outer end of the
upper bar (f) of the lever B passes through
the upper end of the die or rod K, see more
particularly Fig. 3.

To the inclined bar (g) and about in
line with the bar (j) two guides (d') (d')

are attached by pivots (e'), each guide has a spring (f') bearing against its outer side and a rod (g') passes through the lower end of each guide, said rods passing through 5 oblong slots (h') in the lower ends of the guides and having eccentrics (i') upon them. The rods (g') have set screws (j') bearing against them to prevent them from turning casually, the screws (j) passing 10 into the bar (g) as shown in Fig. 3.

L is a bar which is attached to the inclined bar (g) by screws (k'). The bar L projects outward from the bar (g) at nearly right angles and has an upright plate (l') 15 attached to one of its sides. Within the plate (l') at its inner end a plate M is pivoted at (m'). This plate projects above the upper edge of the plate (l') and has two shoulders (n) (n') formed on it, as shown 20 plainly in Figs. 1 and 3.

The plate M is bent around the lower end of plate (l') extends upward and is pivoted to a bar (o') which bar is pivoted to the outer end of the upper bar (f) of the 25 lever B.

The operation is as follows: The bar G is fitted or placed in the groove (s) in the bed F, and the staples (p') are placed on the plate (l') by hand or by any proper 30 means. The inner most staple bears against a ledge (a'') near the outer most shoulder (n) see Fig. 3. The foot of the operator is placed in the strap C and the lever B is depressed and each time the bar (f) of said 35 lever descends the die or rod K is forced downward and the two shoulders (n) (n') are turned down below the upper edge of the plate (l'). As the arm (f) rises or returns to its original position the shoulders 40 (n) (n') rise above the upper edge of plate (l') and then (n) will raise the inner most staple (p') which will then rest against the shoulder (n') for the staple (u) as it is depressed passes under the inner most staple 45 so that it may raise it on its upward movement. At the next downward movement of the bar (f) and shoulders (n) (n') the staple that was previously raised is allowed to pass over the inner most shoulder (n') and 50 between the guides (d) (d'), and when the die or rod K ascends, said staple passes underneath its lower end the die forcing the staple into the rod G as it descends. It will be understood that a staple is fed between 55 the guides each time the die or rod K ascends so that a staple will be driven in the rod G each time the die or rod K descends. Each time the bar (f) descends the lower arm (w) of the lever I is thrown outward and the 60 inner end of bar J catches against the

staple which is being driven in the rod, and when the staple is driven home a rod (b'') on the bar (f) strikes the upper end of the lever E and throws the lower end of said lever free from the staple previously driven in the rod, and allows the spring A' of the lever I to actuate said lever and the bar J so as to move the bar G along the proper distance, or until the staple last driven shall strike against the lower end of lever 70 E, which returns to its place as the bar (f) ascends and in time to serve as a stop.

The spaces between the staples may be lengthened or shortened by adjusting the slide D and the bed F may be so grooved or 75 arranged as to receive any form or shape of rod G, that is used.

In case two or more staples should be fed between the guides (d') they will give or 80 spring outward so that they can be discharged without difficulty and without breaking or disarranging any of the parts, and the guides by adjusting rods (g') may be placed nearer together or farther apart according to the size of the staple.

This machine has been practically tested and it operates effectually and rapidly. The plate (l') may be made sufficiently long to hold a large number of staples so that it will not require to be filled too often.

Having thus described my invention what I claim as new and desire to secure by Letters Patent, is,

1. The means employed for feeding the staples (p') between the guides (d') (d') 95 and underneath the die or rod, K, that is to say, the plate M, pivoted to the plate (l') on which the staples are placed and provided with the shoulders (n) (n'), the plate being connected with the bar (f) by means of the 100 rod (o') substantially as shown and described.

2. I also claim feeding the rod G underneath the guides (d) (d') to receive the staples (p'), by means of the bar J, attached to the bent lever I in connection with the lever E, said parts being operated by their respective springs A' (u) and also by the bar (f) as described.

3. I further claim the guides (d') (d') 110 arranged substantially as shown to convey the staples to the rod and at the same time also allowed to expand so as to prevent the clogging of the same, in combination with the die or rod K for driving the staples into 115 the rod.

BYRON BOARDMAN.
